HENRY A. ARMSTRONG, OF BROOKLYN, NEW YORK, ASSIGNOR TO INTERNATIONAL
TYPESETTING MACHINE COMPANY, OF NEW YORK, N. Y., A CORPORATION OF NEW
YORK.

FIRST ELEVATOR FOR TYPOGRAPHICAL MACHINES.

1,129,941.

Specification of Letters Patent.

Patented Mar. 2, 1915.

Application filed April 18, 1914. Serial No. 832,890.

To all whom it may concern:

Be it known that I, HENRY A. ARMSTRONG, a citizen of the United States, residing at Brooklyn, in the county of Kings and State 5 of New York have invented new and useful Improvements in First Elevators for Typographical Machines, of which the following is a specification.

The present invention relates to improvements in typographical machines of the linotype class wherein lines of previously composed matrices are presented to a mold and a slug cast therefrom, and it is directed more particularly to that portion of the machine known as the first elevator which 15 serves to carry the lines of matrices, after they have been assembled, from a receiving position down to the casting position, then up to the transfer position after the cast 20 has been made where the lines of matrices are transferred to the distributing mechanism, the elevator finally returning to its normal position ready to receive another line of matrices.

25 The primary object of the invention is to provide improved means for holding the matrices in place in the first elevator to prevent dropping or displacement of the matrices, including means for releasing the 30 holding means, at the times when the elevator is to receive or remove a line of matrices with respect thereto, and when the line is brought to the casting position.

To these and other ends, the invention 35 consists in certain improvements and combinations and arrangements of parts, all as will be hereinafter more fully described, the novel features being pointed out particularly in the claims at the end of the specification.

In the accompanying drawings:—Figure 1 is a front elevation of the first elevator and related parts of a typographical machine equipped with the present invention, 45 the elevator being shown in its uppermost position; Fig. 2 is a view of Fig. 1 looking toward the left; Fig. 3 is a front elevation of the first elevator with the latter in position to receive a line of matrices; Fig. 4 is a 50 view of Fig. 3 looking toward the left; Fig. 5 is a front elevation of the upper portion of the first elevator approaching its lower or casting position; Fig. 6 is a view of Fig. 5 looking toward the left.

Similar parts are designated by the same 55 reference characters in the several views.

The preferred embodiment of the invention is shown in the accompanying drawings and will be hereinafter described in detail. In the present instance the invention 60 is shown in connection with a typographical machine of the well known linotype class. It will be understood, however, that the invention is not restricted to the precise construction shown, as equivalent constructions 65 and arrangements within the scope of the annexed claims will be included.

In the present instance 1 designates the first elevator slide of the form usually employed in machines of this class, the slide 70 being guided to reciprocate vertically on a vise frame 2, and its upper end is provided with a head 3 which extends rearwardly and overhangs the vise frame. The overhanging head of the first elevator is provided with a 75 pair of front and rear jaws 4 and 5 which are spaced apart and held in fixed relation by an interposed block 6 forming a channel between them to receive and guide a line of matrices M. A pair of vise jaws 7 and 8 are 80 provided which are adapted to receive between them a line of matrices lowered to the casting position by the first elevator, these vise jaws operating in the well known way to clamp the line endwise in position before 85 the mold.

9 designates a portion of the distributor channel which is adapted to receive the line of matrices from the first elevator after a cast has been made and the first elevator 90 has ascended to its uppermost position, the line of matrices being removed from the distributor channel and distributed into the appropriate magazine channels in the well known or any suitable way.

95 10 designates the delivery channel through which the line of matrices is brought into a position to be received by the first elevator when the latter occupies an intermediate position. Fig. 3 shows a line of matrices 100 about to be received by the first elevator. Fig. 5 shows a line of matrices about to be received between the vise jaws, and Fig. 1 shows a line of matrices in the act of being removed from the first elevator to the distributor channel.

105 It has been found in practice that after the matrices have entered the first elevator

it is desirable or necessary to provide means to prevent them from falling back or out of the channel of the first elevator while they are being elevated and lowered in said elevator, owing to vibration of the machine, movements of the justification parts, and other causes. Heretofore, it has been customary to provide spring-actuated detents to retain the matrices but such have proven more or less unsatisfactory for the reason that they occasion considerable friction upon the matrices as they enter and leave the elevator, and where positively-acting detents have been proposed complicated mechanism is required to release them before the line can be withdrawn.

The present invention provides a positive gate which extends entirely across the channel of the elevator, and means is provided, which is controlled according to the position of the elevator, for opening the gate at the times when the matrices are to enter or leave the first elevator. In the present instance the gate is in the form of a rod or bar 11 which is carried by the first elevator and is reciprocable through the jaw 4, this rod being capable of occupying either a position wherein it will extend across the matrix channel of the elevator, as shown in Fig. 6, or a position where it is retracted and will permit a line of matrices to enter or leave the channel of the first elevator freely or without obstruction. This rod 11 is operatively connected to a rock shaft 12, carried by the first elevator, by a crank or lever 13. A torsion spring 14 acts normally to rotate the shaft 12 in a direction to move the rod 11 into a position to close the matrix channel in the first elevator and to maintain it in such position. The rod 11, however, is retracted at those times when a line of matrices is to be received by or removed from the elevator. In the present instance the shaft 12 has a set of arms 15, 16 and 17 fixed thereon and projecting to one side thereof at different elevations corresponding to the respective positions to be occupied by the elevator. A pair of cams 18 and 19 are also provided, the cam 19 being fixed to the vise frame and having an upwardly and forwardly sloping face adapted to act on the lowermost arm 17 as the elevator approaches and reaches its uppermost position, and the cam 18 being adapted to act upon the arms 16 and 15 to retract the rod 11 when the elevator is receiving a line of matrices and when the line of matrices is about to be introduced between the vise jaws 7 and 8. The cam 18 acts on the arms 16 and 15 successively while the elevator is descending, and in order to permit the arms 15 and 16 to freely pass this cam during the upward movement of the elevator the cam operates substantially as a latch, it being pivoted in the present

instance at 20, and a pin 21 serves to support it normally in operative position while a pin 22 serves to limit its movement when swung aside by the upward movement of the arms 15 and 16, as shown in Fig. 3.

The operation may be briefly described as follows: When the elevator is in its normal receiving position, the arm 16 engages the cam 18 and the rod 11 is thereby held out of the matrix channel of the elevator, as will appear from Figs. 3 and 4. As soon as the elevator begins its descent, the arm 16 disengages from the cam 18, thereby permitting the rod 11 to move across and close the matrix channel in the magazine under the influence of the spring 14, thereby securely holding the matrices from sliding back or otherwise becoming dislodged. As the elevator approaches the casting position, the arm 15 engages the cam 18 so as to withdraw the rod 11 before this rod can reach the vise jaw 8, thereby permitting the elevator to descend and introduce the line of matrices between the vise jaws 7 and 8. After the casting operation the elevator rises to the upper position to transfer the line of matrices to the distributor channel 9, as shown in Fig. 1. While the line of matrices is carried upwardly past its receiving position the rod 11 remains in closed position, the arm 16 merely deflecting the cam 18 as it passes said cam. As the elevator approaches its uppermost position, the arm 17 thereon rides upon the cam 19, thereby rotating the shaft 12 in a direction to withdraw the rod 11 and thereby open the matrix channel, permitting the line of matrices to be removed from the magazine without obstruction. After the matrices have been removed, the elevator descends to its normal receiving position, as shown in Figs. 3 and 4, the arm 16 engaging the cam 18 and causing rotation of the shaft 12 in a direction to retract the rod 11 and thus again open the channel in the elevator to receive the next line of matrices.

According to the present invention the matrix channel of the elevator is entirely free of obstructions at those positions where the matrices enter or leave it while the channel is completely closed at all other positions.

I claim as my invention:—

1. In combination, the first elevator having a channel adapted to receive a line of matrices, a gate or rod normally extending all the way across said channel, and automatic means for retracting said gate when the elevator is in the positions for the receiving or withdrawal of the matrices.
2. In combination, the first elevator having a channel adapted to receive a line of matrices, a movable rod or bar at the entrance thereof extending into said channel from one side, and automatic means con-

trolled by the position of the elevator for withdrawing said bar to allow the matrices to enter or leave the channel.

3. In a machine of the linotype class, the combination with the first elevator having a channel to receive a line of matrices, carry the same to the casting point, and discharge the matrices therefrom, of a gate, and means controlled according to the position of the 10 elevator for causing said gate to completely close the entrance end of the matrix channel thereof at all times except when the elevator is in a position to receive or discharge a line of matrices and in casting position.

15 4. In a machine of the linotype class, the combination with the first elevator having a channel to receive a line of matrices and operative to lower such line to the casting point and raise the line to the discharge 20 point, of a gate movable across the entrance end of said channel, and means controlled by the movement of the elevator for opening

said gate only when the elevator occupies a position to receive or discharge a line of matrices and is at the casting level.

25

5. In a machine of the linotype class, the combination with the first elevator having a channel to receive a line of matrices and operative to lower such line to the casting point and then raise the line past the receiving 30 point to the discharge point, of a gate to close the entrance end of said channel, and means for opening said gate when the elevator is at the receiving, casting and discharge levels, said means being inoperative 35 while the elevator moves past the receiving point toward the discharge point.

In testimony whereof I have hereunto set my hand in presence of two subscribing witnesses.
